UNITED STATES PATENT OFFICE.

JOHN KOPP, OF CINCINNATI, OHIO.

VIOLIN.

SPECIFICATION forming part of Letters Patent No. 431,722, dated July 8, 1890.

Application filed October 9, 1889. Serial No. 326,414. (No model.)

To all whom it may concern:

Be it known that I, JOHN KOPP, a citizen of the United States, and a resident of the city of Cincinnati, in the county of Hamilton and State of Ohio, have invented certain new and useful Improvements in Violins, of which the following is a specification.

The several features of my invention and the various advantages arising from their use 10 conjointly or otherwise will be apparent from the following description.

In the accompanying drawings, forming part of this specification, Figure 1 represents a violin embodying my improvements and 15 having the top removed to show the invention. Fig. 2 is a view of the under or inside surface of the separable top of my violin. Fig. 3 is a cross-section of a completed violin, showing 20 my improvements and taken at the line $x-x$ of Fig. 1. Fig. 4 is an enlarged view in cross-section of the joint between the top and side of the violin.

In repairing violins it frequently becomes necessary to remove the top. In this operation 25 the instrument is always damaged to a greater or less extent and is usually modified in tone. To provide a violin with a separable top has been the object of my invention.

The top A is provided on its under surface 30 with the flange a , which is made to fit snugly within the sides of the instrument. When this flange alone is provided, the top may be secured to the rest of the body, and the pressure of the flange against the sides, especially 35 when the strings are tightened, is sufficient to hold the top in place. The instrument so made, however, is not satisfactory in tone because of a rattling of the flange against the sides. To prevent this, I preferably provided 40 the bracket B, which is attached to the sides of the instrument and extends around the greater part or all of the sides, as shown in Fig. 1. This flange is provided with the upturned lip b , which forms between itself and the sides of the instrument the groove b' , into 45 which the flange a rests when the top is put in place. The flange a , fitting tight within the groove b' , is prevented from rattling. To more certainly check rattling, I preferably 50 line both sides of the groove b' with a cork lining c . This cork lining is a thin layer of cork, which is applied on one side of the groove to the lip b , and on the other side a similar

thin layer of cork is used to face the side of the violin where it forms one of the walls of the groove b' . I also preferably face the top of the sides with a layer of cork c' , which intervening between the top A and the sides of the violin acts to restrain any rattling which might occur in this position. 55

When the top is put on, the flange a rests in the groove b , and all parts being made to fit snugly no glue or other form of fastening is required to hold the parts together. The 60 stringing of the violin, of course, acts as an additional means for holding the top in place. When it becomes necessary to remove the top, it can readily be separated from the sides by inserting a sharp knife or other suitable instrument between the top and the sides, when 65 the top may be readily lifted from its place.

What I claim as new, and desire to secure by Letters Patent, is—

1. The combination of a violin and a separable top provided with a downwardly-projecting flange fitting within the sides of the instrument, substantially as and for the purposes specified. 75

2. The combination of a violin-body having a bracket projecting from its sides internally, 80 an upwardly-projecting lip from the bracket, and a top having a flange adapted to fit the groove between the bracket-lip and the sides of the instrument, substantially as and for the purposes specified. 85

3. The combination of a violin-body having a bracket projecting from its sides internally, an upwardly-projecting lip from the bracket, forming a groove between itself and the sides of the violin, cork facing on the sides of the 90 said groove, and a top having a flange adapted to fit the said groove, substantially as and for the purposes specified. 95

4. The combination of a violin-body having a bracket projecting from its sides internally, 100 an upwardly-projecting lip from the bracket, forming a groove between itself and the sides of the violin, cork facing on the top of the said groove, cork facing on the sides of the said groove, and a top having a flange adapted to fit the said groove, substantially as and for the purposes specified.

JOHN KOPP.
